ROBERT N. EAGLE, OF WASHINGTON, DISTRICT OF COLUMBIA.

Letters Patent No. 98,936, dated January 18, 1870.

IMPROVEMENT IN LAMP-CHIMNEYS.

The Schedule referred to in these Letters Patent and making part of the same

To all whom it may concern:

Be it known that I, ROBERT N. EAGLE, of Washington, in the District of Columbia, have invented new and useful Improvements in Lamp-Chimneys; and I do hereby declare that the following is a full, clear, and exact description thereof, reference being had to the annexed drawings, making part of this specification, in which—

Figure 1 is an elevation.

Figure 2 is a side elevation.

Figure 3 is a plan.

Figure 4 is a transverse section.

This invention relates to improvements in that class of chimneys which is in common use on kerosene-lamps.

My improvements consist in—

First, a modification in the form of the chimney, designed to increase the intensity of the light, and allow of and sustain a freer and more natural spread of the flame, thereby removing one great cause of the liability to breakage of the chimney; and

Secondly, in forming upon the edge of a flat chimney a series of bead-like projections, formed by depressions cut in the mould, at the seam where the two parts of the mould join.

In the annexed drawings—

A represents the base of the chimney, of a form and size to adapt it to the burner upon which it is to be placed.

The throat, or base deflector, is formed in the ordinary manner, by converging the sides at B, for the purpose of diverting the ascending currents of air, and directing them against the flame, thereby to increase its intensity.

Above the throat the body C is expanded, so as to acquire an oval form, as shown in the drawings. The longest diameter of the body should be such as to afford a free and natural expansion of the flame, without bringing the edges thereof in such near proximity to the glass as to produce fracture, or to chill the ascending gases, and cause them to smoke the inside of the chimney.

From the point where the body, in expanding, attains its fullest width, which should be opposite what would be the widest part of the flame, it is extended upward, still preserving, or nearly preserving, in its general outline or profile, its longest diameter, nearly to the top, as shown in fig. 1, but tapering slightly in the direction of its shortest diameter, as shown in fig. 2, until it reaches the point D, where it is suddenly contracted, forming a more or less abrupt shoulder in the line of its longest diameter, and terminating in a more or less flattened elliptical mouth or neck, E, such mouth or neck being carried to any desired height above the shoulders, according to the intensity it is intended to give the draught.

The effect of the shoulders, at D, is to form what I call dead-air recesses, in which will be detained, as it flows through the chimney, air, in sufficient quantity, and so conditioned, as that with the assistance of the super-deflector, hereinafter referred to, the intenser heat arising from the flame shall be prevented from acting in full force directly upon the shoulders D or mouth E, at both of which points a chimney is especially liable to fracture, from the effect of sudden contraction and expansion.

While thus contracting in the line of the longest diameter of the ellipse, I prefer to slightly increase the diameter in the direction of the short axis of the ellipse, as shown in fig. 2.

I have shown the mouth or neck E as being slightly oval, which form I prefer for the style of chimney shown, but it may, without endangering the effectiveness of the chimney, or departing from the principle of my invention, be either more elliptical, as indicated in dotted lines in fig. 3, or round, as in ordinary chimneys.

It will be observed, also, that the chimney, while parallel or gradually tapering on the sides or edges, to the shoulder at D, has also its flattened faces converging to a line horizontal with the shoulders, and breadthwise across the chimney, at or below the point of the shoulder D. The sides of the chimney at this section should be flat, or but slightly convex.

This convergence of the flattened faces of the chimney, at or near the point above designated, I will call the super-deflector, inasmuch as by such convergence or depression of the faces toward each other a throat is formed, through which, as has already been described, in connection with the shoulders D, the heated currents, in their ascent, are deflected toward the shoulders, and thus diverted in their passage to the mouth or exit apertures.

In constructing chimneys which are blown in moulds, or made after the manner of pressed glass, I propose to form, upon the edges of the flat portion of such chimneys, rows of bead-like concavo-convex protuberances, formed by cutting depressions in the mould, where the two parts which form the mould meet. These protuberances may be of any form, according to fancy, and those in the base of the lamp may be formed to receive springs upon the lamp-burner, to hold the chimney in its proper position in relation to the flame of the lamp.

I am aware that such protuberances have been introduced into the modes of ornamenting chimneys, and I therefore do not claim them broadly, but only the prescribed arrangement upon the edges of a flat chimney, or on the base, in line with the flat flame.

I am aware, also, that chimneys are in use, the body of which is elliptical, and which, from the point of its greatest breadth, is contracted to terminate in an elongated cylindrical neck or mouth; but my improved

chimney differs from them in this: that the body, from the point of its greatest breadth, (at or about on a line horizontal with the top of the flame,) is carried upward to the top, or nearly to the top of the chimney, still preserving, or nearly preserving the same breadth as below; or that, in other words, the body is elongated in direction of its height, with sides either parallel or but slightly contracted, to a point near the top of the chimney, and thence, from the point at D, abruptly contracted toward the neck or base of the mouth E, forming a shoulder on either side of the said neck, substantially such as shown, it being observable that the neck or mouth E may be more or less extended above such shoulders, as may be desirable for intensifying the draught.

By this mode of constructing the upper part of a chimney, a proper breadth of draught is secured, to insure equal combustion to all parts of the wick, and a fuller spread of the flame secured and maintained, without impingement of the flame at the sides or edges of the chimney, to cause smoking or fracture, or of inclining the flame to burn centrally, as when the neck or terminating-mouth gradually tapers from a greater breadth below, to an exit-aperture placed opposite to the centre of the bulge, or widest part of the chimney below, as is the case of ordinarily-constructed chimneys.

Having thus described my invention,

What I claim as new, and desire to secure by Letters Patent, is—

1. A glass chimney, the elliptical body of which is

elongated, with parallel or nearly parallel sides, abruptly contracted at E, forming shoulders on either side of the neck or mouth E, substantially as shown and set forth.

2. A glass chimney, with an elliptical body extended in the direction of its height, and terminating in a mouth, which has a greater diameter in the direction of the depth or thickness of the chimney than has the body C at a point immediately below such mouth or neck, as shown in fig. 2.

3. A glass chimney, the parts shown at A, B, C, D, and E of which are respectively formed, substantially as set forth.

4. A lamp-chimney, having rows of concavo-convex bead-like protuberances placed along the seam formed by the joints of the mould, and in the vertical plane of the flame, substantially as set forth.

5. A flattened chimney, having shoulders at D, to form dead-air recesses, substantially as set forth.

6. A glass chimney, the sides or edges of which are parallel or gradually converging, and the flattened faces of which are also converged, to form a super-deflector below the mouth, substantially as set forth.

In testimony whereof, I have signed my name to this specification, in the presence of two subscribing witnesses.

R. N. EAGLE.
